UNITED STATES PATENT OFFICE

HAROLD J. LE VESCONTE, OF CHICAGO, ILLINOIS, ASSIGNOR TO UNION SPECIAL MACHINE COMPANY, OF CHICAGO, ILLINOIS, A CORPORATION OF ILLINOIS

BAG

Application filed June 30, 1928. Serial No. 289,501.

The invention relates to new and useful improvements in bags, and more particularly to the closures for the bag.

An object of the invention is to provide a bag which is closed by stitching with an adhesive applied along the line of stitching so as to prevent the escape of the contents of the bag through the perforation formed by the needle.

10 In the drawings which show by way of illustration one embodiment of the invention:

Figure 1 is a side elevation of a portion of the bag showing the needle side of the stitches and showing the adhesive applied thereto.

15 Fig. 2 is a sectional view on an enlarged scale taken on the line 2—2 of Fig. 1.

Fig. 3 is a view of the opposite side of the bag from that shown in Fig. 1.

The invention is directed to a bag closure 20 which is particularly adapted for closing paper bags. Prior to the invention it has been customary to enclose the side walls of the bag at the mouth thereof with a fabric strip folded so as to enclose the edge portions

25 of the side walls of the bag. A line of stitching passes through the fabric and through the paper side walls of the bag. When a double chain thread stitching mechanism is used the enchain thread loops lying along

30 one face of the fabric strip effectively close the needle punctures, and prevent the escape of the material through the needle punctures. On the needle side of the stitches the needle

35 thread passes into and out of a needle puncture and the strain on the thread tends to open the needle puncture. It is particularly these punctures on the needle side of the closure that it is necessary to close to prevent the escape of material in the bag.

40 The present invention resides in the applying of an adhesive along the stitching line as the stitches are formed. This adhesive not only fills the needle puncture on the needle side of the closure, but the adhesive will be absorbed by the stitching threads and the wall of the binding strip, and also by the bag, and thus very effectively seal the bag preventing the escape of the finest material enclosed within the bag.

45 Referring more in detail to the drawings,

there is shown in Figure 1 a portion of a bag having side walls 1 and 1'. These side walls at the mouth of the bag are enclosed within a fabric strip 2. The fabric strip 2 lies along the outer face of one side wall and is folded 55 over the top of the side walls and lies along the outer face of the other side wall. The needle thread is indicated at 3 in the drawings. This needle thread is passed in loop form through the fabric strip in the side 60 walls of the bag and emerges from the other side of the fabric strip. The needle thread loops are indicated at 3^a. These needle thread loops are interlocked by a looper thread 3^b, which of course is formed into 65 loops. The loops 3^a and 3^b interlocking with each other fairly well cover the punctures in the face of the strip lying against the wall 1' of the bag. The needle enters the fabric strip 2 from the side of the bag opposite these en- 70 chained thread loops. The needle punctures are indicated at 3^c in the drawings. The needle thread passes from one puncture to the next puncture, and when the threads are drawn tight there is a slight tendency of the 75 threads to open this needle puncture 3^a.

During the formation of the stitches an adhesive is applied to the closing seam at the needle side of the formation of the seam. This adhesive is indicated at 4 in the drawings, and is supplied in such a quantity as to form a strip extending along the line of 80 stitches which may completely cover the needle thread. The adhesive will be absorbed by the fabric strip and the stitching thread, and also the walls of the bag as indicated by the shaded portion in Fig. 2 of the drawings. This adhesive completely closes the needle 85 punctures on the needle side. The adhesive, together with the enchain thread loops, form an effective seal for the bag preventing the escape of the finest material when placed in the bag.

90 While the invention is particularly applied to a bag wherein the sides are formed of paper, it will be equally useful with other types of material, and particularly all such fibrous material as will retain an opening 95 formed by the perforating needle. While it is preferred to use a fabric strip for enclos- 100

ing the edge portions of the bag so as to aid in the anchoring of the closing stitches, it will be understood that other material may be used for this purpose, and from certain aspects of the invention the binding strip may be omitted. The adhesive is preferably applied during the forming of the line of stitches, but may be otherwise applied, and may be applied to the thread along both sides 10 of the bag mouth if desired. It has been found in practice that this adhesive not only closes the needle punctures, but also greatly reinforces the seam by cementing the needle thread to the material of the bag.

15 Having thus fully described my invention, what I claim as new and desire to secure by Letters Patent, is:—

1. A bag having side walls, a closing strip folded about the mouth of the bag and engaging the outer faces of the side walls, a line of stitches including a needle thread formed into a series of loops and passing through the strip and the side walls of the bag, and a looper thread formed into loops interlocked 25 with the needle thread loops and covering the needle punctures in the strip against which the said looper thread loops are laid, and a strip of adhesive applied to the line of stitches on the side of the bag opposite the looper 30 thread loops, said strip of adhesive filling and closing the needle punctures in the closing strip against which the adhesive strip is applied.

2. A bag having side walls, a line of stitches 35 passing through and joining said side walls, a strip of adhesive applied to the line of stitches on the side of the bag entered by the needle, said strip of adhesive filling and closing the needle punctures in the closing strip 40 against which the adhesive strip is applied.

In testimony whereof, I affix my signature.
HAROLD J. LE VESCONTE.
